APPARATUS FOR PROCESSING CORD

George P. Bosomworth, Akron, Ohio, assignor to
The Firestone Tire & Rubber Company, Akron,
Ohio, a corporation of Ohio

Application May 4, 1944, Serial No. 534,127

4 Claims. (Cl. 28—59.5)

This invention relates to means for processing cord, and especially relates to apparatus for producing improved rubber-reinforcing cord.

One process of the type relating to the present invention is that wherein cord which is to be used as reinforcing in a fan belt is immersed in a latex bath and then dried, the cord initially being drawn from one spool and ultimately being wound up upon a second spool. Ordinarily this process involves the use of a constant speed wind-up mechanism and tension is obtained on the cord by the use of a brake on the let-off means that controls unrolling the cord from the spool on which it is initially wound. In this process, the factors of speed and tension of the cords are so interlocked that it is difficult to obtain either to any predetermined figure, with any degree of accuracy. Furthermore, the tension on the cord at the wind-up means is equal to the drag on the cord at the let-off means, plus whatever intermediate friction may develop between the two points. This means that the cord is subjected to a rather unknown or uncontrollable maximum tension, with the tension, of course, on the cord varying at various places in the cord processing apparatus.

It is an object of the present invention to provide a novel, improved apparatus for processing cord uniformly to produce high tensile strength rubber-reinforcing cord of uniform properties.

Another object of the invention is to provide an uncomplicated cord treating apparatus in which the wind-up speed of the cord does not control the tensioning of the cord as it is being treated.

A further object of the invention is to provide an easily operated, inexpensive apparatus for processing various portions of a continuous cord or other elastic material, such as fabric, uniformly as it passes through the apparatus.

The foregoing and other objects will be manifest as the specification proceeds.

In the accompanying drawing:

Figure 1 is a diagrammatic elevation of one embodiment of the invention; and

Figure 2 is a diagrammatic plan view of cord driving means of the apparatus of Figure 1.

Referring in detail to the accompanying drawing, there is shown a continuous length of cord 10, which originally is wound upon a spool 11, that is journaled on a shaft 12 and that usually has a drag or brake (not shown) associated therewith to keep the cord taut as it is drawn from the spool. The cord 10 is drawn from the spool 11 by means of cylindrical rolls 13, 13 which are driven at constant speed and which

have the cord wound therearound in several convolutions so as to obtain a "purchase," or grip on the cord. The rolls 13 have a plurality of annular corrugations in their faces, as shown, but may comprise a plurality of narrow pulleys which are abutted on and turn with a common shaft. One of the rolls 13 may be driven through a non-reversible worm gear 34 by any suitable means, such as an induction motor 35, to rotate the roll at a constant speed. Usually the second roll 13 is not positively driven except by the cord passing therearound.

In being drawn from the spool 11, the cord may pass over a guide pulley 14, and next pass to a liquid bath, in this instance latex 16, contained in a tank 15. The latex is of any suitable composition and properties and may be either naturally or artificially created. The cord 10 is led around vertically aligned rolls 17 and 18 while in the tank 15. Auxiliary rolls 19 under spring pressure hold the cord against the rolls 17 and 18, as it passes therearound and cause a certain amount of deformation to facilitate impregnation. Wet cord from the tank 15 then passes around the rolls 13 which are adapted to advance the cord convolutions along the rolls whereby the cord is led into the rolls at one end thereof and drawn off at the other end of same, as shown in Figure 2.

After the cord passes around the constant speed rolls 13, 13 it is then drawn through a drying oven 22, and the cord is subjected to a uniform constant tensional pull set up thereon through rolls 23, 23, which are similar to the rolls 13 and also obtain a "purchase" or grip on the cord 10. However, the rolls 23 differ from the rolls 13 in one material regard in that one of the rolls 23 usually is driven by a direct current, constant torque motor 36 which is of the permanent magnet type and has a wound rotor. Since the radius of the rolls 23 is constant, the constant torque motor sets up a constant tension on the cord so that, in all events, the cord, as it passes from the set of rolls 13, 13 to the rolls 23, 23, has a constant tension exerted thereon, which tension is uniform through out any length of material processed. A feature of the invention is that this tension is controlled solely by the peripheral speed of the rolls 23 with relation to the peripheral speed of the rolls 13. The motor driving the rolls 23 should have a constant torque over a fairly wide speed range in order to maintain constant tension on the cord 10.

Any suitable means may be used to heat the drying oven 22, thus a current of hot air may be

passed therethrough, or heating means may be contained in the drying oven to heat same.

After the cord passes around the set of rolls 23, 23, the cord may again be immersed in a fluid bath, which fluid would be the same, ordinarily, as that contained in the tank 15; hence the cord 10 passes, for example, around a pulley 24 which is immersed in a tank 25 that contains latex 26. As the cord is drawn out of the bath 26, it is led around a guide pulley 27 and into a drying oven 29, the cord being wound around a series of pulleys 28 suitably journaled in the drying oven 29. Ordinarily the pulleys 28 should be vertically spaced and be positioned at the end of the oven, as shown. The oven 29, may be associated with or be part of the oven 22, and may be heated in any desired manner.

The dry cord from the oven 29 is led around a roller 31 and then to a wind-up reel 32, which has level winding means 33 associated therewith to distribute cord evenly over the reel 32. A further feature of the process is that the reel 32 is driven by a motor 37 which has a constant horsepower output over about at least a 3 to 1 speed range and which exerts a constant tensional force upon the cord 10 between the rollers 23, 23 and the wind-up reel 32 and winds up the cord 10 at a speed equal to the let-off lineal speed of the cord from the spool 11 plus the increase in length of the cord due to its stretch under tension. The motor driving the reel 32 produces this tension upon the cord regardless of the amount of cord wrapped upon the reel, so that the radius of pull, or torque set up by the reel 32 may vary but the actual tensional force on the cord remains constant for a large increase over the original radius of the reel 32; for example, an increase in diameter of the reel from 3 to 12 inches due to the cord wound thereon. The wind-up rate is substantially constant but varies slightly to compensate for slight variations in the degree of stretch of the cord under the constant tension exerted thereon.

In the apparatus disclosed it is essential that the rolls 13 be driven at a constant speed and the rolls 23, 23 have a constant torque drive applied thereto. Preferably, the reel 32 has a means of driving same so that the pull set up on the cord and the wind-up rate of same is substantially constant. One electrical motor that has proved suitable for use as a driving means 37 for the reel 32 is a series type direct current motor with a large external resistance and with the field for the motor being in series with the armature. Then by using a three phase alternating current driving motor 35 to drive the rolls 13, which motor operates at the desired speed, the cord 10 will be drawn off the spool 11 at the desired rate, and the speed of the motor approaches but does not exceed the synchronous speed thereof. The non-reversible worm gear 34 connecting the motor to the roll will not overrun the motor so as to change the speed at which the cord is drawn off the spool 11.

It is generally desirable to apply the maximum tension to the cord during the heating step immediately following the initial dipping operation, that is, between rolls 13, 13 and rolls 23, 23. A tension in the order of 60 pounds has been found satisfactory in this stage when the cord being processed was a conventional cotton or rayon fan belt reinforcing cord.

After leaving the rolls 23, 23 the cord is ordinarily under a diminished tension imparted thereto solely by the windup means 32. Thus,

the higher tension existing in the cord between rolls 13 and 23 is localized therebetween, and is not transmitted to the cord traveling from rolls 23. In the case of a conventional fan belt cord, a tension in the order of 35 pounds has been found suitable to apply by means of the driven wind-up means 32.

Now it will be seen that the tensional force exerted on the cord in the first step of processing 10 same is a known, controllable tension which can be uniformly exerted on various lengths of cord. Furthermore, the rate of wind-up of processed 15 cord upon the wind-up reels does not determine the tension of the cord when wound up, nor does it control the tensional force set up on the cord, 20 or fabric treating processes regardless of the specific steps of same, as long as the cord is to be tensioned and wound up or used at a rate which is to be independent of the tensioning treatment of the cord but which sets up a substantially uniform tension and a uniform residual stretch in the cord.

25 From the foregoing it will be seen that an uncomplicated, easily operated apparatus is provided for processing various lengths of cord or fabric or the like uniformly. At the same time, the apparatus serves to divide, or separate the 30 stretching of the cord from the wind-up rate of the cord, thereby providing two separate, controllable operations which are exerted upon the cord.

The finished cord produced by the present 35 invention has been found to be unusually uniform and of high quality. The cord may be produced to exhibit a very high tensile strength, which does not vary appreciably between various lengths or among different lots of the processed 40 cord. The cord also possesses more uniform cross-sectional dimensions than conventional processed cord, and imparts a longer useful life to a rubber article, such as a fan belt, pneumatic tire or other reinforced rubber article incorporating 45 the cord.

While one embodiment of apparatus of the 50 process of the invention has been completely illustrated and described herein, it will be appreciated that modification may be made without departing from the scope of the invention, as defined in the appended claims.

What is claimed is:

1. In apparatus for uniformly stretching rubber-reinforcing cord, means driven by a constant 55 speed motor for propelling the cord, means driven by a constant torque motor for thereafter applying a predetermined stretching tension to the cord, a third means driven by a motor having a constant power output for winding up the cord, 60 said constant speed motor driving said first-named means through a non-reversible worm gear, whereby the cord is propelled at a constant rate which is independent of the thereafter applied predetermined tension.

65 2. In apparatus for processing cord, means driven by a constant speed motor through a non-reversible worm gear for propelling the cord, means driven by a constant torque motor for thereafter applying a predetermined stretching 70 tension to the cord, means for releasing a portion of said stretching tension from the cord, and an additional means for advancing the cord under a diminished but uniform tension.

3. In apparatus for processing cord, means 75 driven by a motor for propelling the cord, and a

second means driven by a constant torque motor for thereafter applying a predetermined stretching tension to the cord, said first-named motor driving said first-named means through a non-reversible worm gear, whereby the cord is propelled at a constant rate which is independent of the thereafter applied predetermined tension.

4. In apparatus for uniformly processing rubber-reinforcing cord, means for impregnating the cord with latex, means driven by a constant speed motor through a non-reversible worm gear for propelling the cord, means driven by a con-

stant torque motor for thereafter applying a predetermined stretching tension to the cord, means for drying the cord under the stretching tension, means for releasing a portion of said stretching tension from the cord, an additional means for advancing the cord under a diminished but uniform tension, means for impregnating the cord while under said diminished tension, and means for drying the cord while under said diminished tension.

GEORGE P. BOSOMWORTH.
